(57) **CLAIM**

The ornamental design for a display screen or portion thereof with graphical user interface, as shown and described.

DESCRIPTION

The FIGURE is a front view of a display screen or portion thereof with graphical user interface showing the claimed design.

The outermost broken lines in the FIGURE show a display screen or portion thereof, and form no part of the claimed design. The other broken lines in the FIGURE show portions of the graphical user interface that form no part of the claimed design.

UNITED STATES PATENT AND TRADEMARK OFFICE
CERTIFICATE OF CORRECTION

PATENT NO. : D814,496 S
APPLICATION NO. : 29/574742
DATED : April 3, 2018
INVENTOR(S) : Bachman et al.

Page 1 of 1

It is certified that error appears in the above-identified patent and that said Letters Patent is hereby corrected as shown below:

Replace the information in the "Related U.S. Application Data" Item (63) with the following:
--Continuation of application No. 29/540,718, filed on Sep. 27, 2015, now Pat. No. Des. 764,517, which is a continuation of application No. 29/495,143, filed on Jun. 27, 2014, now Pat. No. Des. 743,440, which is a continuation of application No. 29/413,011, filed on Feb. 9, 2012, now Pat. No. Des. 708,637.--

Replace the CLAIM with the following:

--The ornamental design for a display screen or portion thereof with graphical user interface as shown and described.--

Signed and Sealed this
Fourteenth Day of August, 2018

Andrei Iancu
Director of the United States Patent and Trademark Office
